(57) **CLAIM**

The ornamental design for arms of spectacle frames, as shown and described.

DESCRIPTION

FIG. 1 is a front view of the arms of spectacle frames of the present invention.

FIG. 2 is a rear view of the arms of spectacle frames of FIG. 1.

FIG. 3 is a right side view of the arms of spectacle frames of FIG. 1.

FIG. 4 is a left side view of the arms of spectacle frames of FIG. 1.

FIG. 5 is a top right-side perspective view of the arms of spectacle frames of FIG. 1.

FIG. 6 is a top view of the arms of spectacle frames of FIG. 1; and,

FIG. 7 is a bottom view of the arms of spectacle frames of FIG. 1.

The broken lines shown in FIGS. 1–7 are for illustrative purposes only and form no part of the claimed design.
